DEVICE FOR REDUCING THE DE-IONIZATION TIME IN GLOW DISCHARGE TUBES AND THE LIKE

Johan Bertil Westberg, Stockholm, Sweden, assignor to Telefonaktiebolaget L M Ericsson, Stockholm, Sweden, a Swedish company

Application December 3, 1952, Serial No. 323,741

Claims priority, application Sweden December 8, 1951

8 Claims. (Cl. 315—335)

The present invention relates to devices in glow discharge tubes for the purpose of making these swifter in work and thus increasing their fitness for use in counters and the like. For this purpose it is necessary to reduce that time which is needed to enable a glow discharge tube after extinction to regain its whole ignition voltage or at least the greater part of the same. This time is called de-ionization time as it is the ionization condition in the gas atmosphere that determines at which voltage the tube is to be ionized again. This is applicable on the assumption that the voltage is lower than the static ignition voltage obtained without ionization. The de-ionization time may be reduced by choosing a suitable gas filling and a suitable pressure and by giving the electrode system an especial shaping.

In gas discharges there generally appear three types of charge carriers, viz. free electrons, positive and negative ions. The last mentioned ones are generated through storing of electrons in neutral gas molecules. After an extinction produced by the voltage being lowered below the sustaining voltage a de-ionization of the gas atmosphere is begun, whereby the charge carriers on one hand diffuse (ambi-polarly) to electrodes and walls, where they are neutralized, on the other get into direct collision, whereby neutral molecules are again generated (recombination). The characteristic thing for the first-mentioned process is that its velocity decreases with increasing pressure, whereby the diffusion constant is reciprocally proportional to the pressure, while the recombination increases strongly with increased concentration and increased pressure. The diffusion predominates at low pressures, e. g. for pure argon at about 1 mm. Hg and below, whereas the recombination prevails at higher pressures (10 mm. Hg and upwards in pure argon).

In pure rare gases one more kind of particles must be considered, viz. the metastable atoms. These atoms produce new charge carriers even a rather long time after the extinction of the glow discharge, thereby increasing the deionization time most considerably. All rare gases have metastable energy levels, and therefore non-rare multi-atomic gases must be utilized, which lack metastable conditions. Non-rare gases possess a large number of energy levels and are therefore well adapted as additional gases to rare gases, whereby the rare gas atoms swiftly lose their metastable energy to the molecules of the additional gas.

Mixtures of rare gases and non-rare gases have early been used for different purposes. Thus for instance hydrogen gas (alternating with argon and mercury) has been added in small quantities to neon and helium in dim glowing lamps, due to which a lower ignition voltage has been obtained (Penning effect). Nitrogen gas has furthermore been used together with rare gases in incandescent lamps for the purpose of preventing glow discharge between the lead-in wires. An account of these earlier applications is to be found in Espe-Knoll: Werkstoffkunde der Hochvakuumtechnik (Verlag von Julius Springer, Berlin 1936), page 234.

2

The fact of the matter is, broadly speaking, that non-rare gases tend to increase the striking and sustaining voltage in glow discharge tubes. Electronegative gases as oxygen and halogens are especially unsuitable, on one hand because they affect the electrodes, on the other owing to their great electron affinity, which causes a high ignition voltage. A suitable gas is hydrogen gas which however should not be used alone but together with one or more rare gases. The concentration is not critical but can be varied from some per cent up to 15—20%. The de-ionization time is thereby reduced most considerably as appears from the table below. A gas mixture of this type has earlier been used in glow discharge tubes of triode type and in tubes containing a plurality of cathodes for sequential ignition (see for instance the British Patent No. 639,827).

That de-ionization time, which is obtained with gas fillings containing hydrogen gas, is also very much dependent on the pressure (within the area actual for glow discharge tubes) and decreases with increasing pressure. This proves that the recombination is of crucial importance in this respect.

A stronger diffusion to the electrodes is obtained, if one or more electrodes in the tube are connected to a certain voltage after the extinction. This voltage, which is not sufficient to enable the tube to be ionized, is yet sufficiently great to accelerate the diffusion effectively. This may occur either by making the extinguishing pulse so small, that the greater part of the anode voltage is maintained after the extinction or still more effectively by introducing in the tube a screen grid electrode enclosing the anode as well as the cathode and being connected to a voltage over the cathode which is lower than the sustaining voltage. Such a screen has been used in the triode of the above-mentioned British patent. The two-above-mentioned methods for de-ionization, viz. increase of the pressure and introduction of a screen grid electrode, are both impaired by certain drawbacks. The pressure must be great, at least about 70 mm., to be fairly effective and this causes high ignition voltages and current densities, which sometimes is not desirable at all. The screen grid electrode means a great drawback from a technical manufacturing point of view, and causes furthermore that an additional voltage must be supplied to the tube.

The present invention has for a purpose to eliminate the two mentioned drawbacks and like the device with the above-mentioned screen it makes use of the de-ionizing capacity of an electric field.

On the annexed drawing there is shown in Fig. 1 an example of a glow discharge tube according to the invention. In Fig. 2 there is shown a pulse connection of a glow triode and in Fig. 3 another pulse connection of a glow triode.

The tube shown in Fig. 1 is provided with a tube envelope with a conductive coating arranged on the outside. This coating covers wholly or partly the outer surface of the tube envelope. If the coating 1 is connected to a voltage which is constant in relation to the cathode 2 of the tube, the potential of the inner side of the tube envelope will be affected capacitively, so that it can be maintained high after the extinction instead of decreasing with the potential of the anode 3. That time during which the wall potential is maintained high is sufficient to reduce the de-ionization time considerably also in pure rare gas tubes. The greatest effect, however, is obtained in tubes with an addition of a non-rare gas as hydrogen gas to the tube atmosphere. As appears from the table below the de-ionization time is most reduced at low pressures, viz. three to four times, and the remaining difference between different pressures is rather insignificant.

[Table over the de-ionization time (in microseconds) in tubes according to Fig. 1 on the drawing. Cathode material Ni. Rectangular extinguishing pulse on the anode.]

Gas	Pressure, mm. Hg	De-ionization time	
		Without coating	With coating
Ar	20	920	520
Ar + 10% H ₂	6.5	85	19
Ar + 10% H ₂	10	47	13
Ne + 1% Ar + 10% H ₂	16	59	13
Ne + 1% Ar + 10% H ₂	51	70	23

The advantage of the coating on the glass envelope is that it may be applied to any potential whatever and consequently also to earth potential. Thus the wall potential of the inner side becomes the right one automatically.

For obtaining the best result the coating should for alternating currents be connected to the cathode in those cases when the potential of the same is not constant during the extinction. This is shown in Figs. 2 and 3. Fig. 2 shows an example of a pulse connection of a glow triode with an earthed cathode 2. The coating 1 is hereby also connected to earth. 4 indicates an ignition anode, to which ignition pulses are supplied. In Fig. 3 there is shown an example of a pulse connection of a glow triode with an RC-circuit in the cathode connection wire. The reference numerals in Fig. 3 correspond to those of Fig. 2.

The coating 1 may also be replaced by a loose screen, 30 but this should in that case enclose the tube so that the capacity may be maintained.

The device according to the invention is not limited to the embodiments shown on the drawing but may to advantage be applicable to glow discharge tubes of the kind described in application Ser. No. 311,966.

I claim:

1. A glow discharge device comprising an envelope containing a gaseous atmosphere composed of rare gas and hydrogen, an anode, and a cathode and a triggering electrode within said envelope, and an electrode disposed upon the outside wall of said envelope thereto and at least partly covering the envelope, the said outer electrode being connected to a point having a potential during operation fixed relative to the operational cathode voltage and coating capacitatively with the operational potential on the inner side of the envelope for maintaining said

latter potential higher than the anode potential decreasing upon extinction of the device whereby the deionization time of the device is reduced.

2. A glow discharge device according to claim 1, wherein in the said outside electrode is in form of an electrically conductive coating applied to the outer wall of said envelope and covering the said wall at least partly.

3. A glow discharge device according to claim 1, wherein in the said outside electrode is in form of a screen closely hugging the configuration of the outer wall of said envelope.

4. A glow discharge device according to claim 1, wherein in said outside electrode is connected to a constant potential.

15. 5. A glow discharge device according to claim 1, wherein in the said outside electrode is connected to the cathode.

6. A glow discharge device according to claim 1, wherein in the said envelope contains at least three electrodes.

20. 7. A glow discharge device according to claim 6, wherein in the said envelope includes electrodes arranged to maintain a continuous small discharge.

25. 8. A glow discharge device comprising an envelope containing a gaseous atmosphere composed of rare gases and hydrogen, an anode, a cathode and a trigger electrode within said envelope, an electrode disposed on the outside of the envelope at least partly covering the same, said outer electrode, for alternating current, being directly connected to the cathode.
